CLAIM

(21) Appl. No.: **29/277,048**

The ornamental design for a mount for a navigation device, as shown and described.

(22) Filed: **Feb. 12, 2007**

DESCRIPTION

(51) **LOC (8) Cl.** **10-04**

FIG. 1 is a front isometric view of a mount for a navigation device according to the present invention;

(52) **U.S. Cl.** **D10/74**

FIG. 2 is a rear isometric view thereof;

(58) **Field of Classification Search** 340/995;

FIG. 3 is a front isometric view thereof;

364/200, 434, 443, 444, 449, 451, 708.1,

FIG. 4 is a rear isometric view thereof;

364/709.11, 499; 73/178 R; 248/DIG. 4,

FIG. 5 is a front elevational view thereof;

248/121, 160, 229, 284, 291, 291.1—229.26,

FIG. 6 is a right side elevational view thereof;

248/689—690; D10/74; D14/347; 342/351,

FIG. 7 is a rear elevational view thereof;

342/419, 457, 357.06—357.13; 343/702;

FIG. 8 is a left side elevational view thereof;

345/87, 104, 133, 156, 168, 173, 901—905;

FIG. 9 is a top plan view thereof; and,

348/180, 184, 315, 739; 701/206—209, 213,

FIG. 10 is a bottom plan view thereof.

701/214
